UNITED STATES PATENT OFFICE.

BROR ALGOR DE WAERN, OF STOCKHOLM, SWEDEN, ASSIGNOR TO J. & C. G. BOLINDERS MEKANISKA VERKSTADS AKTIEBOLAG, OF STOCKHOLM, SWEDEN, A CORPORATION.

STARTING AND CONTROLLING DEVICE FOR INTERNAL-COMBUSTION MOTORS.

Application filed December 18, 1924, Serial No. 756,851, and in Sweden May 18, 1924.

In such internal combustion motors where the fuel is injected without being previously gasified, it is often necessary to inject a quantity of fuel by hand before starting can take place, and after the motor has been started the governor controlling the length of stroke of the pump during operation must also be controlled by hand according to the prevailing load on the motor.

10 To perform this, access was hitherto only had to comparatively inadequate means, inadequate chiefly for the reason that they were mounted in different places of the motor, so that it was necessary to operate them each 15 per se.

The present invention has for its purpose to unite the said devices into a single device, by means of which the above-mentioned operations may be performed.

20 The invention is principally characterized by a member (or mechanism) adapted to be operated by hand, said member or mechanism being on the one hand so connected with the fuel pump that the latter may be caused to 25 pump by means of the said member or mechanism which, on the other hand, is associated with the governor of the fuel pump in such a manner that this governor may also be adjusted by means of the said member (or mechanism) in accordance with the prevailing load 30 on the motor.

The arrangement may preferably be such that the member operated by hand is adapted to be rotated and screwed so that the same 35 will in a certain angular position, and while it is being turned to and fro, actuate the pump plunger or the member influencing the latter, so as to effect the pumping by hand, whereas, in another angular position, the said member 40 will respectively strain or unload a spring connected therewith, said spring counteracting the deflection of the pump governor driven by the motor.

The accompanying drawing illustrates a 45 device arranged in the manner last set forth. Fig. 1 shows the same in vertical section and Fig. 2 is an external view of the device taken at right angles to Fig. 1.

1 is the plunger of the fuel pump, the suction stroke of which is brought about by the spring 2 while the pressure stroke is effected by the member 3 which is rotatably mounted about the pin 4, and provided with the sliding roller 5 bearing on the cam 6. The latter is 50 displaceably but not rotatably mounted on the

spindle 14 driven by the motor, and is movably connected to the governor weights 7 supported by the spindle 14 and adapted to make deflections, and thereby to displace the cam 6 against the action of the spring 8. The 60 spring 8 is compressed between the cross head 9 of the governor and a casing 10 which latter forms the most prominent detail of the arrangement. The casing 10 is adapted to be rotated and screwed about the fixed body 11 65 surrounding the spindle 14, and is provided on the outside with a handle 12 by means of which the casing may be rotated. The edge of the casing has an abutment 13 which is, prior to the motor being started, situated ad- 70 jacent the part 3.

The handle 12 being grasped so as to turn the casing 10 to the left according to the drawing, the abutment will be caused to actuate the member 3 which is thus, in turn, caused 75 to operate the pump plunger 1 for pumping. In such manner the desired pumping by hand is performed by turning the casing to and fro a sufficient number of times.

After the motor has been started, the casing 80 is again turned in the one or the other direction so that the governor spring 8 is compressed or expanded, according as a larger or smaller quantity of fuel is to be injected.

What I claim as new and desire to secure 85 by Letters Patent of the United States of America is:

1. An arrangement in internal combustion motors for pumping fuel to effect starting and adjustment of the pump governor, including 90 in combination, a support, a spring mounted pump plunger on said support, a stroke regulating member for the plunger, a spring controlled governor coacting with the regulating member and manually operable means arranged about the governor and adjustably engaged with the support so that when adjusted thereon it will actuate the regulating member and thereby the plunger and will in addition effect an adjustment of the spring controlled 95 governor.

2. An arrangement as claimed in claim 1 wherein the manually operable adjusting means includes a cap like member arranged in threaded engagement with the support, a 100 handle extending therefrom and a projection extending from the lower edge of the member for coacting with the stroke regulating member.

3. An arrangement as claimed in claim 1 110

wherein the governor includes a spindle rotatably mounted in the support, a cam slidably mounted on the spindle for coacting with the stroke regulating member governor arms 5 coacting with the cam, a spring surrounding the spindle and acting at one end on the cam and having the other end engaged by the manually operable means, substantially as and for the purposes set forth.

4. An arrangement as claimed in claim 1 10 wherein the stroke regulating member includes a full crank lever pivotally mounted on the support having one arm disposed between the plunger and the manually operable adjusting means and the other arm engaging 15 the governor.

In testimony whereof I affix my signature.
BROR ALGOR DE WAERN.
